UNITED STATES PATENT OFFICE.

JAMES H. GLENN, OF PHILADELPHIA, PENNSYLVANIA, ASSIGNOR TO CHARLES S. WEIERMAN, OF PHILADELPHIA, PENNSYLVANIA.

KNITTING-MACHINE.

1,181,520.

Specification of Letters Patent.

Patented May 2, 1916.

Application filed April 20, 1915. Serial No. 22,652.

To all whom it may concern:

Be it known that I, JAMES H. GLENN, a citizen of the United States, residing at Philadelphia, in the county of Philadelphia and State of Pennsylvania, have invented 5 new and useful Improvements in Knitting Machines, of which the following is a specification.

This invention relates to improvements in 10 circular knitting machines of the type particularly designed and adapted for knitting stockings and like knitted fabrics.

The object of the invention is to provide 15 a knitting machine of the character stated, which is especially designed and adapted for knitting a ribbed elastic fabric, such as a stocking top, and which embodies novel and improved cam mechanism for controlling the needles to obtain a desired knitting 20 action.

The invention consists of the features of 25 construction, combination and arrangement of parts herein fully described and claimed, reference being had to the accompanying

drawings in which:—

Figure 1 is a diagrammatic view of the cam ring of the cam cylinder of a circular knitting machine, showing the arrangement 30 of the cams for controlling one set of needles. Fig. 2 is a similar view, showing the arrangement of the cams for controlling the second set of needles. Fig. 3 is a vertical transverse section, taken substantially on line 3—3 of Fig. 1, through one side of 35 the cam cylinder. Fig. 4 is an elevation on line 4—4 of Fig. 5. Fig. 5 is a top plan view of the same. Fig. 6 is a perspective view of the star wheel and rotary cam member associated therewith. Fig. 7 is a perspective view of the adjustable primary cam 40 of the needle controlling cams. Fig. 8 is a detail view of the stationary latch pin. Fig. 9 is a detail view of the butt ends of the short and long butt needles. Fig. 10 is a 45 vertical longitudinal section through a portion of the machine. Fig. 11 is a fragmentary horizontal section of the same. Figs. 12 and 13 are reverse face views of a 50 section of fabric produced by the machine. Fig. 14 is a transverse section thereof. Fig. 55 15 is a detail view showing the cam held retracted by the latch.

The present invention is intended to provide a machine for producing elastic ribbed

stocking tops of the construction disclosed 5 in my prior application filed Feb. 3, 1915, Ser. No. 5944, wherein the fabric comprises two separate courses of threads each having long and short loops arranged in alternation, the long loops of each course of 6 each thread being interlocked with each other and with the short loops of the adjacent course or courses of the other thread. In producing the required knitting action 65 in the production of such a fabric use is made of two sets of needles in each row, one set having short butts and the other set long butts, in conjunction with a double set of cams in each row, whereby the needles are operated independently of each other to 70 act upon the respective yarns or threads, one set acting on each yarn or thread. In the present structure a novel construction of cam mechanism is employed whereby the same fabric may be obtained by the use of 75 but a single set of cams and a single yarn or thread in conjunction with each row of needles.

The fabric comprises thread courses A and B, arranged in alternation with each 80 other, and of any desired weight and thickness. These thread courses are produced by two operations, by means of the respective sets of needles, from a single strand of yarn, instead of from two strands as in the 85 structure disclosed in my application No. 5,944 aforesaid. Where the fabric disclosed is designed for use as a ribbed elastic stocking top, the stockings are continuously 90 knitted upon a cylinder knitting machine of that kind employing a stationary needle cylinder and a revoluble cam cylinder controlling the action of the needles of the needle cylinder, the body portion of the stocking being knitted in the usual way, 95 while the improved elastic top is knitted in a novel manner by varying the action of the needles. In the operation of continuously 100 making the stockings the toe portions of completed stockings are severed from the tops of adjacent stockings and seamed in the usual way. It will, of course, be understood that the elastic fabric may be made and employed for any of the purposes for 105 which it is adapted.

By reference to Figs. 12, 13 and 14 it will be seen that the course threads A are extended, like the threads B, transversely

of the fabric in courses at desired intervals apart, and that the said threads A are knitted in so as to provide loops *a*, which are long in a vertical direction and short in a transverse direction, and other loops *a'* which alternate with the loops *a* and are long in a transverse direction and short in a longitudinal direction, while the threads B are knitted in so as to provide loops *b* similar to the loops *a* and loops *b'* alternating with the loops *b* and similar to the loops *a'*. As shown, the loops *a* of adjacent courses are interlocked with each other and with the loops *b'*, forming forwardly projecting vertical, longitudinal wales *a²* and rearwardly projecting intervening wales *b²*, said wales being arranged in parallel relation to each other and thus giving the ribbed construction to the fabric. The wales *a²* stand out with a desired prominence from the face of the fabric, while the wales *b²*, by reason of the method of knitting, form with the body of the fabric a substantially smooth and even inner surface, as will be seen by reference to Fig. 12 of the drawings.

It will be observed that the loops *b* of the threads B pass forward through the adjacent loops *a'* of the threads A and interlock with each other, while the loops *b'* of the threads B extend rearwardly from the loops *b* through the loops *a'* and cross the bights of the wales *a²* between the loops *a* and *a'* and thus interlock with both sets of loops *a* and *a'* at their points of juncture. By this construction it will be seen that the long and wide loops *a* and *a'* and *b* and *b'* are knitted in a firm and substantial manner, while at the same time the weave is such as to impart substantially equal loops and curvatures to the threads A and B, so that the fabric may expand and contract in a substantially uniform manner throughout. The construction further provides threads in which the loops or wave portions are such as to secure extreme elasticity in the loops *a'* and *b'*, which are capable of straightening out transversely, and extreme high wave length lines in the loops *a* and *b* longitudinally of the fabric, by which contraction and expansion of these loops in a longitudinal direction is freely permitted. Thus when the tubular stocking top is drawn outward or pulled upon longitudinally it will cause contraction of the meshes, adapting the stocking to snugly fit the limb of the wearer, while any lateral pull or strain will permit the stocking to distend or expand elastically in a lateral or transverse direction, while contracting in the longitudinal direction. Extreme elasticity of the fabric is thus gained without imposing undue strain thereon, the ease of motion of the threads upon one another adapting the fabric to expand and contract without expanding or contracting the individual threads,

and therefore without liability of breakage or snapping of the thread.

As stated, in weaving the elastic stocking top or improved fabric a machine having two sets of needles is employed, the needles of the sets being arranged in alternation with each other. The needles C of one set are each provided with short butts or projections *c*, while the needles C' of the other set are provided with long butts or projections *c'*. One needle of each of these sets with its butt portion is fragmentarily illustrated in Fig. 9. These needles are adapted for coöperation with and are controlled by a set of cam devices D upon the rotary cam cylinder D', of the knitting machine. For the purpose of forming the heels of stockings on knitting machines of this character, it is customary to increase the length of the needles carried by one-half of the needle cylinder E and to provide an additional or duplicate set of cams to control the longer needles, but any suitable arrangement of the needles and construction and arrangement of duplicate cams for this purpose may be employed.

In the action of the machine each needle knits once in a cycle, occurring once in each second revolution of the cam cylinder, and each needle picks up two thread courses before casting its stitch, so as to provide a double loop weave at every stitch. In the structure disclosed, the cam devices 1, 2, 3, 4 and 5 may be the usual cams commonly employed, while the cams 6 and 7 are additional cams employed for coöperation with the usual cams to adapt the machine to produce my improved fabric. The cam 7 comprises a body or plate provided with two cam ribs or projections *7^a* and *7^b*, which intersect at their upper ends and thence diverge in a downward direction in inverted V-formation, the cam rib *7^a* being approximately of one-half the thickness or extent of projection of the cam rib *7^b*. In practice, the cam members may be adjustable in any suitable manner, so that the cams 6 and 7 may be rendered inoperative to adapt the machine to knit in the usual way to produce an ordinary stocking body, and so that said cams may be disposed for operation to change the action of the needles to produce the ribbed elastic stocking top. The cam 7 is adjustable in a direction transversely of the needle cylinder to regulate the action of the cam members *7^a* and *7^b* and the cam mechanism as a whole, the said cam members *7^a* and *7^b* being employed to control the primary vertical movements of the needles to vary and control their action on each revolution of the cam cylinder or one-half the working cycle. The cam member 7 is movable or projectable inwardly to dispose the cam rib *7^a* into the path of the butts of the long butt needles, in which position the

cam rib 7^b will be disposed in the path of the short butt needles and act only upon said needles, the butts c of said short butt needles being passed by the cam member 7^a, while the butts c' of the long needles C' lie in the path of and are engaged by the cam rib 7^a. When the cam 7 moves backward or outward to normal position, however, the cam rib 7^a is withdrawn from the path of both sets of needles, but the cam rib 7^b still projects inwardly so as to be engaged by the butts c' of the needles C'.

In the drawings the dotted lines x and y respectively indicate the lines of motion or courses of travel of the long butt needles and the short butt needles. In the rotation of the cam cylinder, with the cam 7 in the first-named position, the butts of the long butt needles will engage the cam 7^a and be elevated thereby and follow the course indicated by the dotted lines x, while the short butt needles will miss the cam 7^a but strike the cam 7^b and be caused to take the course indicated by the dotted lines y, while when the cam 7 is withdrawn to the normal second-named position both sets of needles will miss the cam 7^a but the butts c' of the needles C' will strike the cam 7^b and follow the course indicated by the dotted line y, the butts c of the needles C meanwhile taking the path x' which converges with the path x at the apex of cam 2. The first action takes place during the first revolution or first half of the working cycle of the cam cylinder, while the second action takes place upon the second revolution or second half of the working cycle of the cam cylinder. In the first action the long butt needles will first be elevated by the cam 7^a, then travel across to the cam 3, then pass downwardly between the cams 2, 3, 4 and 6 and then pass upwardly between the cams 4 and 5, while the short butt needles will strike the cam 7^b, pass downwardly between the cams 1 and 2 and then upwardly between the cams 2 and 6, then downwardly between the cams 4 and 6 and then upwardly between the cams 4 and 5. In the second half of the knitting action, the long butt sets of needles will miss the cam 7^a and strike the cam 7^b thence following course y, while the short butt needles will miss the cam 7^b, engaging with cam 2 and taking the course x' and finally course x. Each long butt needle picks up a loop of yarn while passing downwardly along cam 4 at each of the two revolutions comprising the cycle, thus having two loops of yarn to slip down over the free end of the lowered latch when the long butt needle rises to its highest point at the top of the cam 7^a when the cam carrier 7 is in its innermost position at the beginning of each cycle. These two loops of yarn are cast over the point of the needle during its descent around the

bottom of cam 4 and it will be noticed that the two loops in passing off will close the latch over the first loop of the new cycle, which has just been taken up by the hook of the needle during the descent of the latter along the side of cam 4.

Each short butt needle also picks up a loop of yarn while descending along cam 4 during each of the two revolutions comprising its cycle, casting both loops down over the free end of the lowered latch when the needle rises along the side of cam 2 during the second revolution of the cycle. The two loops of thread on the short butt needle are cast over the end of the needle when the latter reaches the bottom of cam 4, during the first revolution of the cam cylinder in its next succeeding cycle, the needle hook having in the meantime taken on the first thread of the new cycle while descending along the side of the cam 4. While each needle will rise and fall several times in a cycle the long butt needle only knits at the bottom of cam 2 because it was elevated high enough in passing around cam 7^a to drop the loops of thread onto the shank of the needle over the free end of the open latch. Any rise and fall of the needle with the thread above the latch only returns the thread to the hook of the needle. Likewise the short butt needle only knits at the bottom of cam 4 because it has lifted high enough at the top of cam 2 to cast its loops down over the free end of the open latch.

During the first revolution of a cycle the long butt needles rise over the apex of cams 7^a—7^b, pass downwardly along cams 3 and 4 and rise along cam 5, while during the second revolution of the cycle these long butt needles descend along the face of cams 7^b and 2, thence rising along cam 6, descending along cam 4 and rising along cam 5.

During the first revolution of a cycle the short butt needles descend along the side of cam 7^a and cam 2, thence rising, descending and rising along the surfaces of cams 6, 4 and 5 respectively. During the second revolution of the cycle the short butt needles pass both cams 7^a and 7^b, engaging first with the upper face of cam 2, thence with the faces of cams 3, 4 and 5 in turn.

The mechanism for shifting the cam 7 in and out to alternately shift the cam members 7^a and 7^b into and out of the path of the needle butts comprises a supporting bracket E' on which the cam member 7 is slidably supported and guided for movement through an opening E² in the wall of the cam cylinder D'. The cam 7 is provided with an outwardly extending stem or shank f, the outer portion of which is reduced to form a shoulder f', and said stem is movable longitudinally through a guide chamber g formed in the bracket E', the reduced port

tion of the stem projecting outwardly beyond the said bracket. A coiled spring h is disposed within the chamber and between the outer end wall thereof and the shoulder 5 f' , and operates when compressed and released to shift the cam 7 on its inward motion. Mounted to revolve upon the outer end of the stem f is a star wheel I having a desired number of teeth i , four of which 10 are shown arranged equidistantly around the periphery of said wheel. The star wheel I is adapted to engage a fixed abutment P disposed so as to acuate it once on each revolution of the cam cylinder. The wheel I is 15 loosely mounted upon the stem f between a washer j interposed between it and the bracket E' and a pin k projecting diametrically through the stem and having its end portions disposed on opposite sides of the 20 latter. Carried by and preferably formed integrally with the wheel I is a rotary cam member or sleeve l having its outer portion fluted to provide a cam surface consisting 25 of alternating elevations m and depressions m' equal in number to the teeth i , the elevations m being arranged diametrically opposite each other and at an angle of 90° to the depressions m' , which are likewise arranged diametrically opposite each other. These 30 elevations and depressions are adapted for coöperation with the ends of the pin or projections k , so that on successive and alternative quarter revolutions of the star wheel the stem and cam will be moved outwardly by the cam surfaces m and the spring g compressed and tensioned and then 35 permitted by the recession of the pin k within the recesses m' to move inwardly under the reaction of the spring, so that on 40 one revolution of the cam cylinder the cam 7 will be retracted while on the next revolution of the cam cylinder said cam 7 will be projected, the cam 7 being therefore alternately and intermittently projected and retracted to control the needles in the manner 45 heretofore described.

In the type of machine described in the present application two sets of knitting needles are provided one set being disposed 50 in a plane above the other or lower set. Each set of needles occupies but one-half of the entire circumference of the cylinder E, the lower set of needles, moreover, being positioned on one side of the cylinder, while 55 the other or upper set are located on the diametrically opposite side of the cylinder. By this construction, after the cam 7 becomes disengaged from the butts of the needles, it will have to make a complete 60 half revolution of its orbit before again contacting with said needle butts. When the cams 7 are in this relatively idle position, that is, not in engagement with the needle butts, the cam actuating mechanism 65 is operated to move said cam laterally, by

means of which the in and out adjustment of the cam is permitted without interference from the needle butts.

Projecting from the rear or following side of the supporting bracket E', (Fig. 5) 70 is a stud n supporting a fixed latch pin n' notched at its outer end n^2 to engage one side of the aperture o in the stationery latch plate o' . This is designed for use when it is desired to throw the cams 7^a and 7^b out of the paths of the needle butts while 75 the body of the stocking is being knitted. When in this position the star wheel I misses the stud P, and hence is not turned as the cam cylinder revolves. The fixed 80 latch pin n' also carries a spring o^2 which engages the teeth i of the star wheel I so as to prevent excessive revolution of the latter when it strikes the actuating stud P. On the first quarter revolution the pin k will 85 engage the cam surface m and retract the cam 7 while tensioning the spring j , and on its succeeding movement the pin k will engage the recesses m' , thus permitting the cam 7 to be projected by the expansion of 90 said spring. As a result, the cam 7 will be controlled and alternately shifted into its two working positions to govern the action 95 of the needles as hereinbefore set forth. Hence it will be seen that the knitting action 100 described and fabric produced thereby will be secured by the action of the two sets of needles upon different portions or thread courses of a single continuous yarn through a knitting action involving in its cycle two 105 complete revolutions of the cam cylinder, on each of which the needles have different actions, whereby the loops in the thread courses are formed and interlocked together.

I claim:—

1. In a knitting machine, two sets of needles, a rotary cam ring having stationary cam members providing two courses of travel, an adjustable cam member on the ring having surfaces for coöperation with the respective sets of needles to adapt said sets of needles to take different courses, and means for adjusting said adjustable cam to its different positions on alternate revolutions of the cam ring. 110

2. In a knitting machine, two sets of needles, provided with projections of different lengths, a rotary cam ring having stationary cam members providing two courses of travel, an adjustable cam member on the 120 ring having surfaces for coöperation with the projections of the needles to take different courses, and means for adjusting said adjustable cam to its different positions on alternate revolutions of the cam ring. 125

3. In a knitting machine, two sets of needles, a rotary cam ring having fixed cam members arranged to provide two courses of travel, an adjustable cam member on the cam ring having cam surfaces of different 130

extents of projection for coöperation with the stationary cams and the respective sets of needles to adapt said sets of needles to take different courses, and means for adjusting said adjustable cam to different operative positions to respectively dispose its surfaces for action on alternate revolutions of the cam ring.

4. In a knitting machine, needles provided with long and short butts, a rotary cam ring carrying cam surfaces arranged to provide two courses of travel for the needle butts, an adjustable cam member having cam surfaces of different extents of projection, said cam member being adjustable to project its surfaces relatively to the needle butts, means operative on each revolution of the cam cylinder for adjusting the adjustable cam to one working position, and means operative through the aforementioned means on the succeeding rotation of the cylinder to move the adjustable cam member to a different working position.

5. In a knitting machine, two sets of needles respectively having short and long butts, a rotary cam cylinder carrying stationary cams providing different courses of travel for the needle butts, a controlling cam provided with two cam surfaces having different extents of projection, said controlling cam being adjustable across the path of rotation of the needles, a stem connected with the cam, a star wheel revolubly mounted on the stem, a cam carried by the star wheel and having alternately disposed projections and recesses, a projection on the stem arranged to coöperate with said cam projections and recesses, a spring tensioned by the movement of the stem in one direction when the projections are in engagement, for shifting the stem in the reverse direction when the projection thereon en-

gages the cam recesses, and means operative on each rotation of the cam cylinder for intermittently rotating the star wheel.

45

6. In a knitting machine, two sets of needles, a rotary cam cylinder carrying stationary cams providing different courses of travel for the respective sets of needles, a controlling cam provided with two cam surfaces for coöperation with the respective sets of needles and the said stationary cams to adapt said sets of needles to take their different courses, a star wheel, means operative on each revolution of the cylinder for intermittently rotating the star wheel, means controlled by the star wheel for moving said controlling cam in one direction, and means set for action by the star wheel on such operation of the cam for shifting the cam in the opposite direction.

50

7. In a knitting machine, two sets of needles, a rotary cam cylinder carrying stationary cams providing different courses of travel for the respective sets of needles, an adjustable controlling cam movable into and out of the path of the needles, and provided with two cam surfaces of different extents of projection for coöperation with the respective sets of needles and said stationary cams to adapt said sets of needles to take their different courses, a star wheel having a cam surface, means for intermittently turning said wheel on each revolution of the cam ring, a member upon the adjustable cam for engagement with said cam surface of the star wheel on alternate movements of the latter to effect projection of the adjustable cam, and means set into action on intervening movements of the star wheel to effect the retraction of the adjustable cam.

65

In testimony whereof I affix my signature.

JAMES H. GLENN.
